PUMP WITH DUAL ROTORS

Fred W. Rosentrater, Chicago, Ill.

Application October 16, 1957, Serial No. 690,515

1 Claim. (Cl. 230—141)

This invention relates in general to new and useful improvements in fluid, gases and air pumps and more particularly to a pump used for these purposes having dual rotors.

The primary object of this invention is to provide a pump which includes two internal rotors, the rotors being of such a design and so positioned whereby they create a dual suction and repelling action in the same direction simultaneously with a very minimum amount of resistance.

Another object of this invention is to provide a pump which is so constructed whereby it will efficiently create either a high speed flow and/or a pressure action on fluids and gases of all types and also air.

Another object of this invention is to provide an improved pump which is so constructed whereby the inlet openings thereof are identical whereby the direction of flow through the pump may be varied as is desired.

A further object of this invention is to provide an improved rotor design which is of such a nature whereby a pump incorporating a pair of such rotors disposed in meshed relation and driven in timed sequence will produce a maximum pumping action either of a high speed flow nature or a pressure action with a minimum resistance so as to have a maximum efficiency.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a vertical sectional view taken through the fluid pump which is the subject of this invention, the view being taken between one of the cover plates of the housing of the pump and the body member thereof and shows both the internal cross section of the housing and the relationship of the rotors with respect thereto;

Figure 2 is an elevational view showing the end construction of the fluid pump;

Figure 3 is an enlarged sectional view taken substantially upon the plane indicated by the section line 3—3 of Figure 1 and shows the internal details of the fluid pump;

Figure 4 is an enlarged fragmentary elevational view of the fluid pump with a gear case cover thereof removed in order to show the arrangement of driving gears therein; and

Figure 5 is an enlarged fragmentary view similar to Figure 4 and shows a modified form of drive.

Referring now to the drawings in detail, it will be seen that there is illustrated the dual rotor fluid pump which is the subject of this invention, the pump being referred to in general by the reference numeral 10. The pump 10 includes a housing which is referred to in general by the reference numeral 12. The housing 12 is formed of a central body member 14 and a pair of cover plates 16 and 18. The cover plates 16 and 18 are secured to the body member 14 by means of suitable bolts 20. It is

2

to be noted that suitable gaskets 22 and 24 are disposed between the body member 14 and the cover plates 16 and 18, respectively.

The housing 12 includes a longitudinal axis 26 and a transverse axis 28. The body member 14 is of a configuration whereby it is symmetrical about the longitudinal axis and about the transverse axis. It is also to be noted from Figures 2 and 3 that the body member 14 is of a constant thickness. Disposed at opposite ends of the body member 14 along the longitudinal axis 26 are openings 30 and 32. The openings 30 and 32 are identical and may serve as either inlet or outlet openings. When one of the openings 30 and 32 is functioning as an inlet opening, the opposite one of the openings 30 and 32 functions as an outlet opening.

The cover plate 16 has positioned therein a bearing 34 which is aligned with a bearing 36 carried by the cover plate 18. Extending through the bearings 34 and 36 and suitably journaled therein is a first shaft 38. The shaft 38 projects through the cover plate 16 and functions as a drive shaft. A suitable power source, not shown, will be connected to the drive shaft 38.

The cover plate 16 is provided with a boss 40 in which there is mounted a bearing 42. Carried by the cover plate 18 in alignment with the bearing 42 is a bearing 44. Suitably journaled in the bearings 42 and 44 and extending through the bearing 44 is a second shaft 46. The shafts 38 and 46 are spaced along the transverse axis 28 and are spaced equidistant on opposite sides of the longitudinal axis 26.

Carried by the shaft 38 and keyed thereto by means of a key 48 is a hub 50 of a rotor 52. Extending outwardly from the hub 50, which is of a small diameter, is a plurality of radiating blades 54. The blades 54 are of a flat configuration and are rectangular in outline. It is to be noted that the blades 54 are of a constant cross section.

Keyed to the shaft 46 by means of a key 56 for rotation therewith is a small diameter hub 58 of a second rotor 60. The rotor 60, like the rotor 52, includes a plurality of blades 62 which radiate from the hub 58. The blades 62 are flat and rectangular in outline. It is to be noted that the blades 62 are of a constant cross section. From the foregoing description of the rotors 60 and 52, it will be readily apparent that the rotors are identical. It is also to be noted that the blades of the rotors 52 and 60 closely engage portions of the housing 12 to assure a proper seal therewith. Also, the blades 54 and 62 intermesh and are disposed closely adjacent the hubs 58 and 50, respectively, during their rotation to further provide a suitable seal.

In order that the rotor 60 may be driven in an opposite direction and in timed sequence with the rotor 52, the cover plate 18 has extending rearwardly therefrom a pair of idler shafts 64 and 66. The idler shafts 64 and 66 are disposed in spaced relation along the transverse axis 28 and are intermediate the shafts 38 and 46. Keyed on the shaft 38 is a gear 68 which is meshed with a gear 70 which is freely rotatably mounted on the idler shaft 64. The gear 70 is meshed with a gear 72 which is freely journaled on the idler shaft 66. The gear 72 is in turn meshed with a gear 74 which is keyed to the shaft 46.

It is to be noted that the cover plate 18 includes a gear case 76 in which the gears 68, 70, 72 and 74 are positioned. The gear case 76 has a removable cover plate 78 which is retained in place by bolts 80.

Referring now to Figure 5 in particular, it will be seen that there is illustrated a modified form of cover plate 82 which replaces the cover plate 18. The cover plate 82 differs from the cover plate 18 primarily in that the idle shafts 64 and 66 are omitted. Keyed on the

shaft 38 is a pulley 84. A similar pulley 86 is keyed on the shaft 46. Entrained over the pulleys 84 and 86 is a driven belt 88 which has a central portion thereof crossed as at 90 whereby the shafts 38 and 46 are driven in opposite directions at the same rate.

The pulleys 84 and 86 and the drive belt 88 are disposed within a case 92 formed integral with the cover plate 82. The case 92 is provided with a removable cover (not shown) which is held in place by a plurality of bolts 94.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

A pump comprising a hollow housing, said housing including a central body member and spaced cover plates, said housing having a longitudinal axis and a transverse axis, identical inlet and outlet openings in said body member, said inlet and outlet openings being in alignment along said longitudinal axis, a pair of shafts disposed in spaced relation along said transverse axis and equally spaced on opposite sides of said longitudinal axis, bearing means carried by said cover plates journaling said shafts for rotation, a rotor carried by

each of said shafts for rotation with said shafts, said rotors being disposed in meshing relation, drive means connected to a first of said shafts for rotating said shaft, connecting means connecting said first shaft to a second of said pair of shafts for rotating said shafts in opposite directions and in timed relation, said connecting means including a pair of idler shafts disposed along said transverse axis on one of said cover plates intermediate said first mentioned shafts, meshing drive gears on all of said shafts.
